UNITED STATES PATENT OFFICE.

JOHN H. GAVIN, OF CHICAGO, ILLINOIS, ASSIGNOR TO THE L. WOLFF MANUFACTURING COMPANY, OF SAME PLACE.

DESIGN FOR A WASHBOWL AND SLAB.

SPECIFICATION forming part of Design No. 23,894, dated December 25, 1894.

Application filed September 4, 1894. Serial No. 522,139. Term of patent 14 years.

To all whom it may concern:

Be it known that I, JOHN H. GAVIN, a citizen of the United States, residing at Chicago, in the county of Cook and State of Illinois, have 5 invented and produced a new and original Design for a Corner Washbasin and Slab, of which the following is a specification, reference being had to the accompanying drawing, forming a part hereof.

10 The drawing shows a perspective view of a wash basin and slab embodying my design.

The leading feature of my design consists of the peculiar decoration on the outer surface of the bowl.

15 The bowl A is of an oval or elliptical form and has on its outer surface at the lower or central portion thereof a series of wide and narrow flower leaf like decorations $a a'$, and

20 at its upper edge a semi-annular horizontal rim a^2 which unites with and forms part of the horizontal slab B. In the belt or zone between the rim a^2 and the decorations $a a'$

is a double scroll like decoration a^3 interspersed with pointed leaf work a^4 as illustrated in the drawing. The two members D 25 of the vertical corner slab unite at an angle at the corner and have ogee curved outlines $d d$ at their ends which unite with the horizontal slab B, the same being furnished with ogee curved outlines $b b$ at the two extremities thereof, and which ogee curves $b b$ blend with the general oval curve of the rim a^2 , as 30 is clearly illustrated in the drawing. The general effect of the rim a is continued at the vertical back D D by a marginal decoration or belt $c c$.

I claim—

The design for a corner wash bowl and slab herein shown and described.

JOHN H. GAVIN.
